UNITED STATES PATENT OFFICE.

ALLAN M. HIRSH, OF MONTCLAIR, NEW JERSEY, ASSIGNOR TO LOCK JOINT PIPE COMPANY, OF NEW YORK, N. Y., A CORPORATION OF NEW JERSEY.

SECTIONAL CONCRETE PIPE AND METHOD OF MAKING SAME.

1,004,570.

Specification of Letters Patent.

Patented Oct. 3, 1911.

Application filed March 12, 1909. Serial No. 482,953.

To all whom it may concern:

Be it known that I, ALLAN M. HIRSH, a citizen of the United States, residing at Montclair, county of Essex, and State of New Jersey, have invented certain new and useful Improvements in Sectional Concrete Pipes and Methods of Making Same, of which the following is a full, clear, and exact description.

10 My invention relates to sectional concrete pipes or conduits, and pertains more particularly to the joint between the sections. In work of this kind the pipe sections are commonly constructed with so-called "bell 15 and spigot" ends, that is, each section has a reduced end which enters and is secured in the internally rabbeted end of the adjoining section; the ends being so formed as to have a circumferentially extending 20 groove inside or outside, or part inside and part outside, the pipe, which groove is then filled with concrete thereby securing the sections together. In the case of pipe in which the groove is on the inside it is difficult to 25 fill the upper part of the groove effectively, even when the pipe is large enough in diameter to permit a workman to enter the same and work in a sitting or standing posture, and it is therefore the object of my 30 present invention to construct the pipe sections in such manner as to avoid the necessity of working from the inside to fill the upper part of the groove; in other words, to permit the upper part to be filled from 35 the outside of the pipe.

In the annexed drawing I have illustrated the preferred form of the invention, and referring now thereto, Figures 1 and 2 are perspective views of the bell and spigot 40 ends, respectively, of my improved concrete pipe. Fig. 3 is a side elevational view showing two sections assembled with the upper part of the groove or key-space unfilled. Fig. 4 is a longitudinal section showing two 45 sections assembled, with the key-space filled. Fig. 5 is a transverse section showing the inner form or centering, which closes the bottom of the upper part of the key-space, in position for the deposit of concrete in 50 said space.

The pipe sections, two of which are shown at 1, 2, are formed by molding in the usual way, and may be of any suitable form in cross section, for example cylindrical, as 55 shown. One end of each section is formed

with an axially extending rim or lip 3, around its inner circumference, said lip or extension being tapered on its outer surface as shown and constituting the "spigot". The other section, 2, which is to be connected to the spigot end of the first, has an outer lip or extension 4, on the lower side of the section only, said outer lip or flange extending more or less than half around the circumference of the pipe, as may be desired, and constituting the "bell". The upper part is cut away so as to leave a space between the two sections, as clearly shown in Fig. 3 and around the edge of the cut away part the pipe section has a shallow 60 groove, as shown at 5, Fig. 4. The lip or flange 3, constituting the spigot, is shorter than the bell 4, so as to leave a groove 6, Fig. 4, on the inside at the bottom of the two sections, and the inner edges of the sections 70 are inclined so as to give an under-cut to the groove, as shown in the figure just mentioned.

Embedded in each section is a suitable meshed reinforcement, 7, preferably a layer 80 of so-called "expanded metal", the ends of which project from the edge or body of the pipe inside the bell 4, and from the spigot 3, so as to overlap when the two sections are placed together, as in Fig. 3.

The two sections being assembled in the manner shown, the groove inside the pipe is packed full of concrete, embedding the overlapping reinforcing fabrics. An inner form or centering is next placed in position 85 to close the bottom of the open space at the top of the pipe. This centering consists preferably of two radial members 8, 9, crossing each other at right angles and a curved plate 10, of suitable material supported 90 thereon and braced by radial members 11. The centering being placed in position and raised firmly against the top of the pipe by a wedge 12 driven under the foot of the upright member 9, the channel or space at the 95 top of the pipe can be packed full of concrete from the outside with the greatest convenience and despatch. When the filling has set the inner centering is removed, leaving the pipe sections effectively bound 100 together by the engagement of the concrete key with the overlapping meshed fabric used as the reinforcement. The centering leaves the inner surface of the pipe smooth 105 and clear at the top, and of course the con- 110

crete in the groove at the bottom can be smoothed off while still soft, by means of any suitable implement. The joint between the two sections having been completed, a 5 third section can be secured to either of the first two in the same manner, and so on until as many sections as desired are assembled.

It will be noted that the concrete deposited 10 in the inner groove 6 and in the open space at the top of the pipe is continuous or unbroken around the circumference of the pipe, thus in fact constituting a monolithic key which not only serves to bind the sections 15 together by its engagement with the overlapping meshed reinforcing fabric, but also insures against leakage at the joint, as frequently happens in the case of pipe in which the outside key-way, at the top of the pipe, 20 is a mere groove and not a space extending clear through the pipe-wall as in my construction.

What I claim is:

1. The herein described method of making 25 sectional concrete pipe, which consists in forming pipe-sections with a bell-end having the upper portion of the bell cut away and with a spigot end shorter than the bell, and with a meshed reinforcing 30 fabric projecting out of the spigot at one end and out of the body of the section, within the bell, at the other end; assembling the sections with the spigot of one extending into the bell of the other, with the projecting 35 meshed reinforcing fabrics overlapping in the groove formed inside the pipe at the bottom between the spigot of the one section and the body of the other and in the open space left by the cut-away bell at the 40 top; filling the said groove with concrete from the inside of the pipe and embedding the meshed reinforcing fabrics overlapping therein; arranging a centering or temporary closure at the bottom of said open space to 45 close same at the inside of the pipe; filling said space with concrete from outside the pipe and embedding the meshed reinforcing fabrics overlapping therein; allowing the embedding concrete to set; and removing the 50 centering or temporary closure; substantially as described and for the purposes set forth.

2. The herein-described sectional concrete pipe, comprising a pipe-section having at one end a bell with the upper part thereof 55 cut away; a pipe section having at one end a short spigot extending into the bell on the other section, and leaving a groove at the bottom on the inside of the pipe and an open space at the top, said sections having

embedded meshed reinforcing fabrics projecting into said groove and space and overlapping therein; and a circumferentially continuous key of concrete filling said groove and space and embedding the meshed reinforcing fabrics overlapping therein; substantially as described and for the purposes set forth.

3. The herein-described sectional concrete pipe, comprising a pipe section having at one end a bell with the upper part cut away; a 70 pipe section having at one end a short spigot extending into the bell on the other section, and leaving a groove at the bottom on the inside of the pipe and an open space at the top, the groove at the bottom registering 75 with the space at the top, said groove and space being filled with concrete thereby forming a monolithic key.

4. The herein described method of making a pipe joint which consists in forming one 80 section of a pipe with a bell end having the upper portion thereof cut away, and forming the abutting section with a spigot end shorter than the bell; assembling the sections 85 whereby a groove is left in the bottom defined by the projecting portion of the bell and by the short spigot, said groove below being continuous with the space above; filling the groove below then filling the space above with concrete; and then allowing the 90 concrete to set, thereby producing a monolithic key; substantially as described and for the purpose set forth.

5. The herein described method of making a pipe joint which consists in forming one 95 section with a bell and having the upper portion cut away and with a spigot end shorter than the bell and with a meshed reinforcing fabric projecting out of the spigot at one end and out of the body of the section 100 within the bell at the other end; assembling the sections with the spigot of one extending into the bell of the other with the projecting fabrics from the sections overlapping 105 each other; filling the groove with concrete from the inside of the pipe and embedding the overlapping reinforcing fabrics therein, and filling the said space on the outside with concrete embedding the overlapping reinforcing fabrics therein; and then allowing 110 the concrete to set; substantially as described and for the purpose set forth.

In testimony whereof I affix my signature in the presence of two subscribing witnesses.

ALLAN M. HIRSH.
